UNITED STATES PATENT OFFICE

2,203,381

GARMENT HANGER

James D. Coney, Detroit, Mich., assignor to Star-
Service Hanger Company, Detroit, Mich., a
corporation of Michigan

Substituted for abandoned application Serial No.
135,744, April 8, 1937. This application May
15, 1939, Serial No. 273,625

20 Claims. (CL 223—88)

This invention relates to improvements in garment hangers.

The main objects of my invention are,

First, to provide a garment hanger comprising a yoke member having a pair of downwardly diverging spring wire arms and a transverse strut extending therebetween and supported thereby in a novel manner.

Second, to provide a hanger of the type described having provision for ready assembly of the strut with the hanger arms, and further provision whereby the hanger arms serve to clampingly bind and retain the strut.

Third, to provide a hanger of the type described characterized by means at the free ends of a pair of downwardly diverging arms for receiving and frictionally retaining a transverse strut, and further means whereby outward displacement or shifting of the strut is prevented by the abutment thereof with said arms.

Fourth, to provide a hanger of the type described and embodying arms, the free ends of which are configured in a particular manner and disposed obliquely to exert spring binding action on the strut member held thereby.

Fifth, to provide a hanger of the type described which is simple in its parts, inexpensive of production, and readily assembled by unskilled persons.

Referring to the drawing, Fig. 1 is an elevational view of the hanger of my invention having a yoke formed of wire and a pair of downwardly diverging arms, the initial or disassembled position of the arms being indicated in dotted lines.

Fig. 2 is an end elevation of the structure of Fig. 1, viewed from the right of that figure, and further illustrating details of the invention.

Fig. 3 is a fragmentary enlarged detail illustrating the engagement of the end of a strut in the formed terminal of one of the hanger arms.

Fig. 4 is a fragmentary view in perspective illustrating a modified form or embodiment of my invention.

Fig. 5 is a fragmentary elevational view illustrating another modified form.

Fig. 6 is a view in vertical section illustrating a construction wherein a hollow strut is employed.

This is a substitute for abandoned application Serial No. 135,744, filed April 8, 1937.

The present invention deals with a garment hanger characterized by a transverse cylindrical strut of substantial diameter as compared with the diameter of the wire forming the yoke supporting the strut, to the end that a more

adequate supporting surface will be furnished for garments draped on the hanger. My invention particularly concerns itself with the provision of means for effectively securing the ends of the strut to the free ends of the diverging arms of the yoke, a frictional binding or clamping action at the point of engagement of the arms with the strut as well as spring clamping action of the arms being relied on to secure the parts.

Referring to the drawing, the reference numeral 1 in general indicates a yoke formed of wire conformed to provide a twisted shank 2, a wire suspension member or hook 3, and a pair of downwardly diverging arms 4, the said arms initially being disposed sharply downwardly, as illustrated in dotted lines in Fig. 1. A transverse strut 5, which may be a cylindrical spindle or shaft of wood if desired or a solid or hollow elongated cylindrical member of any other suitable material, is supported between the ends of the arms 4. By initially disposing the arms to enclose a relatively sharp angle, it will be apparent that when a strut is operatively associated with the arms, the latter will be spread outwardly and placed under considerable spring tension tending to urge the arms toward one another.

For the purpose of receiving the ends of the strut 5, I bend the free ends 6 of the arms 4 downwardly, then inwardly and upwardly, terminating the so bent free ends in rounded eyes 7. The ends of rod 5 are inserted in eyes 7. However, in order to exert spring binding or clamping action on the rod or strut 5 to retain the same in the eyes, I initially dispose the eyes obliquely at a substantially sharper angle to the horizontal than when the eyes are in final position with the strut inserted therein. In other words, the strut must first be inserted in one of the eyes 7, then an upward bending or springing effort exerted on the eyes in order to insert the strut in the other eye. This will cause the upper and lower portions of the respective eyes to bindingly engage the upper and lower sides of the strut in a manner which will be obvious and resist displacement of the strut. Reference to the drawing discloses that the ends of the strut longitudinally abut the curved free ends 6 of the arms 4, thus preventing outward shifting or accidental removal of the strut.

As previously stated, the strut may be of any suitable material and cross-sectional shape. For example, in the case of a wooden strut, I preferably employ a member three-eighths inch thick. Fig. 6 illustrates the use of a hollow tubular

strut 8, but other details of the invention as previously and subsequently described are applicable equally when a hollow strut is employed.

In Fig. 4 I disclose a modified form of my invention wherein the free end 6 is bent downwardly, thence upwardly through 180 degrees to form a double wire abutment 9, thence inwardly at 10, and terminates in an eye 11 encircling strut 5 and frictionally binding the same, in the same manner as described above, due to the initial oblique positioning of the eye, as referred to.

In Fig. 5 I illustrate an alternative form of my invention, the parts of which are similar to that illustrated in Figs. 1, 2 and 3, and are accordingly numbered the same, the distinction lying in the form that in the modification of Fig. 5 the eyes are disposed reversely or the free ends have been bent initially past the vertical and must be sprung inwardly for insertion of the strut. In Fig. 5 the initial positioning of the arm obliquely to effect a distinct gripping action on the strut 5 is illustrated in dotted lines.

From the foregoing the advantages of my construction are apparent. The elements, namely, the wire element 4 and strut 5, are capable of being readily and cheaply formed by machinery now known, and are furthermore capable of being quickly assembled by unskilled labor. In assembled position the parts are strongly attached to one another to resist displacement and the support furnished by the enlarged strut 5 overcomes objections which have heretofore characterized struts of thin wire construction by eliminating the formation of sharp creases in garments supported thereby. The gripping effect of the arms 4 is enhanced by the initial disposal thereof for springing during assembly, and due to the effect thereof I find that I am enabled to utilize a wire of decidedly smaller diameter than is ordinarily employed in metal hangers.

I have illustrated and described my improvements in the embodiment which I consider practical. I have not attempted to illustrate or describe other embodiments or adaptations, as it is believed that this disclosure will enable those skilled in the art to embody or adapt my improvements as may be desired.

Having thus described my invention, what I claim as new and desire to secure by Letters Patent is:

1. In a garment hanger, a yoke comprising a pair of downwardly diverging arms connected at one end to a shank, said arms at their free ends being bent downwardly, inwardly and upwardly, and terminating in obliquely disposed eyes, and an elongated cylindrical strut extending between the free ends and receivable in and frictionally engageable with said eyes, whereby the strut is supported, said strut at its outer ends longitudinally abutting said arms to prevent shifting of the strut outwardly, said strut flexing said eyes when inserted therein whereby the spring binding effect thereof is increased.

2. In a garment hanger, a yoke comprising a pair of downwardly diverging arms connected at one end to a shank, said arms at their free ends being bent inwardly and upwardly and terminating in eyes, and an elongated strut extending between the free ends and receivable in said eyes whereby the strut is supported, said strut at its outer ends longitudinally abutting said arms to prevent shifting of the strut outwardly, said strut flexing said eyes when inserted therein whereby the spring binding effect thereof is increased.

3. In a garment hanger, a yoke comprising a pair of downwardly diverging arms connected at one end to a shank, said arms at their free ends being bent downwardly, inwardly and upwardly, and terminating in obliquely-disposed eyes, and an elongated cylindrical strut extending between the free ends and receivable in and frictionally engageable with said eyes whereby the strut is supported, said strut flexing said eyes when inserted therein whereby the spring binding effect thereof is increased.

4. In a garment hanger, a wire yoke having downwardly diverging spring arms, the free ends of said arms being bent toward one another and upwardly and terminating in eyes, and a rod receivable at its ends in said eyes and longitudinally abutting said arms, said eyes being obliquely disposed relative to said rod whereby spring binding action thereon is effected by said eyes, said spring arms being substantially spread from their rest position by said rod whereby spring retaining action is exerted on the rod.

5. A garment hanger comprising a yoke having downwardly diverging arms, and a transverse strut extending between and carried by the free ends of said arms, said arms terminating in portions disposed obliquely to said strut, said portions externally engaging and being distorted by said strut to exert spring frictional retaining action on said strut, said arms having means integral therewith for abutting the ends of said strut to restrain the same from outward movement.

6. A garment hanger comprising a yoke having downwardly diverging arms, and a transverse strut extending between and carried by the free ends of said arms, said arms terminating in portions disposed obliquely to said strut, said portions externally engaging and being distorted by said strut to exert spring frictional retaining action on said strut.

7. A garment hanger comprising a yoke having downwardly diverging arms, and a transverse strut extending between and carried by the free ends of said arms, said arms terminating in portions externally engaging and being distorted by said strut to exert spring frictional retaining action on said strut, said arms having means integral therewith for abutting the ends of said strut to restrain the same from outward movement.

8. A garment hanger comprising a yoke having downwardly diverging arms terminating in eyes, and a strut extending between the free ends and receivable in and frictionally engageable with said eyes, said strut springing said eyes from normal position whereby the eyes bindingly engage the strut, said strut at its outer ends longitudinally abutting said arms to prevent shifting of the strut outwardly.

9. A garment hanger comprising a yoke having downwardly diverging arms terminating in eyes, and a strut extending between the free ends and receivable in and frictionally engageable with said eyes, said strut springing said eyes from normal position whereby the eyes bindingly engage the strut.

10. A garment hanger comprising a yoke having downwardly diverging arms, the ends of said arms carrying rod engaging portions, and a rod receivable at its ends in said portions, said portions externally engaging and being distorted by said rod whereby spring binding action is effected thereon.

11. A garment hanger comprising a wire yoke

having downwardly diverging arms curved inwardly at the ends thereof, the incurved ends terminating in upwardly disposed strut-receiving eyes, and a strut engaged in said eyes, the arms 5 of the yoke being normally spaced substantially less than the length of the strut so that when distended and the strut is engaged within the eyes, the eyes are under clutching stress by the turning moment resulting from the stress of the 10 arms of the yoke and the distortion of the eyes from their initial position relative to the arms of the yoke.

12. A garment hanger comprising a wire yoke having downwardly diverging arms terminating in inturned ends, the said inturned ends being provided with upwardly directed eyes, and a strut 15 engaging said eyes, the arms of the yoke, when the eyes are engaged with the strut, being placed under stress acting to bow them inwardly and 20 the eyes being subjected to a turning moment whereby they are held under clutching engagement with the strut.

13. A garment hanger comprising a wire yoke having downwardly diverging arms turned inwardly at the ends thereof, the inturned ends terminating in laterally-disposed strut-receiving eyes, and a strut engaged in said eyes, the arms 25 of the yoke being normally spaced substantially less than the length of the strut so that when distended and the strut is engaged within the 30 eyes, the eyes are under clutching stress by the turning moment resulting from the distortion of the yoke from its initial position.

14. A garment hanger comprising a wire yoke 35 having downwardly diverging arms terminating in inturned ends, the said inturned ends being provided with laterally-disposed eyes, and a strut engaging said eyes, the eyes being in spring clutching engagement with the strut.

40 15. A garment hanger comprising a support, a pair of wire arms downwardly diverging from the support, and a rod connecting the lower portions of the arms, said portions being hooked inwardly and upwardly and terminally forming eyelets receiving the rod, the eyelets being disposed with their axes substantially in the plane determined by said arms, the arms forming abutments to resist disengagement of the rod from 45 the eyelets.

50 16. A garment hanger comprising a support, a

pair of spring wire arms downwardly diverging from the support, and a rod connecting the lower portions of the arms, said portions forming hooks extending toward each other and terminating in upward projections oblique to and apertured to 5 receive the rod, the hooks being sprung, in engaging the rod, to reduce the obliquity of said upward projections, whereby the spring reaction of the hooks binds their upward projections on the rod to restrain the latter from rotation. 10

17. A garment hanger comprising a support, a pair of spring arms downwardly diverging from the support, and a rod connecting the lower portions of the arms, said portions forming a pair of eyelets receiving the rod, and such eyelets being originally so axially disaligned as to impose a spring stress on the lower portions of the arms, in engaging the rod with the eyelets, whereby the eyelets bind upon the rod in reaction to such stress, and thus resist rotation of the rod. 15 20

18. A garment hanger comprising a pair of joined downwardly-divergent wire arms, a pair of eyelets formed upon the lower ends of said arms, and a rod inserted in and jointly carried by the eyelets and restrained by the eyelets from 25 accidental rotation, and a support engaging the arms at their juncture.

19. A garment hanger comprising a support, a pair of wire arms downwardly diverging from the support, and a rod connecting the lower portions of the arms, said portions being bent toward each other and terminally forming eyelets receiving the rod, the eyelets being disposed with their axes substantially in the plane determined by said arms, and the arms forming abutments to resist disengagement of the rod from 30 the eyelets. 35

20. A garment hanger comprising a support, a pair of spring wire arms downwardly diverging from the support, and a rod connecting the lower portions of the arms, said portions extending toward each other and terminating in eyelets receiving the ends of the rod, the eyelets being axially disaligned prior to their engagement by the rod and being stressed toward an aligned 40 relation to accommodate the rod, and binding on the rod, in reaction to such stress, and opposing rotation of the rod by such binding. 45
